UNITED STATES PATENT OFFICE.

GEORGE THOMAS MACFARLANE, OF PINNER, ENGLAND.

WINDLASS.

1,323,298.

Specification of Letters Patent.

Patented Dec. 2, 1919.

Application filed September 14, 1918. Serial No. 254,118.

To all whom it may concern:

Be it known that I, GEORGE THOMAS MACFARLANE, a subject of the King of Great Britain and Ireland, residing at Pinner, Middlesex, England, have invented Improvements in Windlasses, of which the following is a specification.

The object of this invention is to provide a simple and efficient windlass adapted to 10 safely control operations involved in casting and weighing an anchor and particularly suitable for being driven by an electric motor. The construction of the improved windlass is such that the anchor can be 15 dropped without the use of the motor, while if it should be necessary the chain lifter can be driven in a lowering direction in order to insure the anchor dropping promptly when desired, the gear for driving the chain lifter 20 in this direction embodying a ratchet and pawl or equivalent mechanism that will allow the chain lifter to overrun the drive upon the speed of the said lifter increasing sufficiently under the action of gravity, the 25 motor and gearing being thereby relieved from shock or jar. The chain lifter is positively driven when hoisting the anchor and a brake is provided for controlling the rotation of the chain lifter in a lowering direction 30 while allowing it to freely rotate in a hoisting direction so that, when hoisting, it is not necessary to release the brake unless the anchor should foul.

In a windlass according to the invention 35 the chain lifters are freely mounted on a shaft that can be positively driven in either direction, as through epicyclic gear adapted to be controlled by brake devices, so that the speed of rotation is determined by the 40 amount of frictional pressure exerted. Means controllable at will are provided for positively connecting each chain lifter to a drum fixed on the chain lifter driven shaft so that the corresponding chain lifter can 45 be positively driven in either direction. Pawl and ratchet or the like mechanism is also provided for connecting the chain lifter to the said drum when said controllable connecting means are withdrawn, the said pawl 50 and ratchet mechanism being adapted to drive the chain lifter in a lowering direction. A brake drum is connected to each chain lifter through a free wheel arrangement that allows the chain lifter to rotate in a hoisting direction notwithstanding the brake being 55 on.

Figure 1 of the accompanying drawing shows in sectional part plan one construction of windlass arrangement embodying the invention.

Fig. 2 is a section through one of the 60 brake drums on the chain lifter shaft.

Fig. 3 is a plan illustrating another type of windlass embodying the invention.

In the windlass shown in Fig. 1 an electric or other motor, not shown, which may if desired be located below the deck, drives a horizontal shaft *a* upon which are keyed the sun wheels *b* of epicyclic gear arranged one at each side of a pinion *c* mounted to 70 freely rotate on the shaft *a* and gearing into a spur wheel *d* fixed on the shaft *e* of the chain lifters *f* of which there are two arranged to freely rotate one on each side of the spur wheel *d*. Beyond the chain lifters 75 the shaft *e* is fitted at each end with a warping drum *f*. The wheels *b* of the epicyclic gear, gear into planet pinions *g* that also gear into rings of teeth *h* carried by brake drums *j* and *k*. The planet pinions *g* at one 80 side of the driving pinion *c* are carried by a structure *m* mounted to rotate freely on the shaft *a*, and on the boss *n* of which is keyed a brake drum *o*, the corresponding brake drum *k* being fixed to the driving pinion *c*. 85 The planet pinion carrier *p* at the other side of the driving pinion *c* is fixed to the driving pinion *c*, the corresponding brake drum *j* being mounted freely on the shaft *a*.

The arrangement is such that by holding 90 the brake drum *o* and releasing the brake drums *j* and *k*, the planet pinion carrier *m* is stationary, the drum *k* with the driving pinion *c* then rotating in one direction, while by releasing the brake drums *k* and *o* and 95 holding the brake drum *j* the planet pinion carrier *p* with the driving pinion *c* are rotated in the other direction.

Keyed upon the chain lifter shaft *e* at either side of the spur wheel *d* is a drum *r* 100 the rim of which is furnished with strong bolts *s* arranged to slide laterally into and out of engagement with holes formed therefor in the adjacent flange *t* of the corresponding chain lifter *f*. These bolts can be 105 actuated by hand. The flanges *t* of the chain lifters adjacent to the drums are provided with ratchet teeth adapted to be engaged by ratchet pawls *w* carried by the drums *r* and arranged to be readily put into or out of 110 action. The housing or mounting of the pawls is of course such that whether the

pawls are in or out of action they will not be liable to injury or to be knocked off the drums by contact with the bed plate of the windlass or other fixed member or obstruction. At the outer side of each chain lifter f is a brake rim x connected to the chain lifter by a free wheel device comprising spring pressed pawls pivoted to the rim x and ratchet teeth formed on the periphery of a drum e^2 fixed on the chain lifter shaft e , see Fig. 2. The rim x is fitted with a brake band y adapted to hold the brake rim. The free wheel device, see Fig. 2, is such that when the brake is on the chain lifter can rotate in a hoisting direction but not in a lowering direction. The ratchet t and pawl w at the other side of the chain lifter are such that when in gear the chain lifter can be rotated, through the drum r fixed on the chain lifter shaft, in a lowering direction.

To cast or let go the anchor with the improved windlass the desired chain lifter f is first connected with the corresponding driving drum r by putting in gear the ratchet and pawl connecting mechanism t , w and, if needful, also taking a whip from the anchor stock, and leading it down the hawse pipe and up over the forward fairleads to a warping end f^1 , the brake x , y is then released and if the anchor does not start the chain lifter f is rotated in the lowering direction by operation of the epicyclic gear brakes and a strain is put on the whip, the drive being transmitted through the drum r on the chain lifter shaft e and the said ratchet and pawl mechanism t , w . So soon as the speed of the chain lifter, due to the falling anchor, exceeds the speed of the drum r the drive will be overrun as before described and then or when the anchor stops, the engine will of course be switched off. The brake x , y , is then tightened and the anchor held. To hoist the anchor the sliding bolts s are moved to secure the driving drum r to the chain lifter f and the chain lifter shaft e is driven in the desired direction by suitably controlling the epicyclic gear. During the hoisting operation the brake x , y , need not be released as owing to its free wheel connection with the chain lifter the latter can rotate in a hoisting direction with the brake on, it being only necessary to release the brake in the event of the anchor fouling while being hoisted.

As will be seen the construction of the epicyclic gear is such that the gear train is arranged within a totally inclosed oil box or bath.

The improved arrangement of chain lifters, locking bolts, ratchet and pawl mechanism and free wheel brake, is not necessarily limited to windlasses driven by epicyclic gear as hereinbefore described but may be applied to any usual horizontal or vertically

arranged windlass with or without warping ends.

Fig. 3 shows in plan an ordinary capstan windlass driven by a vertical steam engine 2 embodying the said improved arrangement. As the corresponding parts are indicated with similar reference letters the construction will be understood from the previous description with reference to Figs. 1 and 2. 75 3 indicates the capstan.

In details of construction variations may be made without departure from the invention as will be understood.

What I claim is:—

1. In a windlass, a shaft, a chain lifter 80 freely mounted on the said shaft, means for rotating said chain lifter, a brake drum, a free wheel device through which said chain lifter is connected to said brake drum whereby notwithstanding the brake being 85 on the chain lifter can be freely rotated in a hoisting direction, and ratchet and pawl mechanism whereby the chain lifter can be positively rotated in a lowering direction.

2. In a windlass, a chain lifter, ratchet teeth on chain lifter, a ratchet wheel rigidly fixed to said chain lifter, a brake rim surrounding said ratchet wheel, ratchet pawls carried by said brake rim and engaging said ratchet wheel, a shaft on which said chain 95 lifter is freely mounted, means for rotating said shaft in either direction at will, a drum fixed on said shaft adjacent to said chain lifter, bolts mounted to slide on said drum and adapted when slid in one direction to 100 engage said chain lifter, and ratchet pawls mounted on said drum adapted to engage ratchet teeth on said chain lifter.

3. In a windlass, a chain lifter, ratchet teeth on said chain lifter, a ratchet wheel 105 rigidly fixed to said chain lifter, a brake rim surrounding said ratchet wheel, ratchet pawls carried by said brake rim and engaging said ratchet wheel, a shaft on which said chain lifter is freely mounted, brake devices, epicyclic gear controlled by said 110 brake devices for driving said shaft in either direction at will, a drum fixed on said shaft adjacent to said chain lifter, bolts mounted to slide on said drum and adapted when slid in one direction to engage said chain lifter, and ratchet pawls mounted on said drum adapted to engage said ratchet teeth on said chain lifter. 115

4. In a windlass, a chain lifter, ratchet teeth on said chain lifter, a ratchet wheel rigidly fixed to said chain lifter, a brake rim surrounding said ratchet wheel, ratchet pawls carried by said brake rim and engaging said ratchet wheel, a shaft on which said chain lifter is freely mounted, a spur wheel mounted to freely rotate on said shaft, a drum fixed to said spur wheel adjacent to said chain lifter, bolts mounted to slide on said drum and adapted when slid in one 120 125 130

direction to engage said chain lifter, ratchet pawls mounted on said drum adapted to engage the said ratchet teeth on said chain lifter, a spur pinion gearing into said spur wheel and means for rotating said pinion in either direction at will.

5. In a windlass, a chain lifter, ratchet teeth on said chain lifter, a ratchet wheel rigidly fixed to said chain lifter, a brake 10 rim surrounding said ratchet wheel, ratchet pawls carried by said brake rim and engaging said ratchet wheel, a shaft on which said chain lifter is freely mounted, a spur wheel mounted to freely rotate on said shaft, a 15 drum fixed to said spur wheel adjacent to said chain lifter, bolts mounted to slide on said drum and adapted when slid in one direction, to engage said chain lifter, ratchet pawls mounted on said drum adapted to 20 engage the said ratchet teeth on said chain lifter, a spur pinion gearing into said spur wheel, a shaft on which said spur pinion is freely mounted, brake devices and epicyclic gear controlled by said brake devices for 25 driving said pinion in either direction.

6. In a windlass, a chain lifter, ratchet teeth on said chain lifter, a ratchet wheel rigidly fixed to said chain lifter, a brake rim surrounding said ratchet wheel, ratchet 30 pawls carried by said brake rim and engaging said ratchet wheel, a shaft on which said chain lifter is freely mounted, a spur wheel mounted to freely rotate on said shaft, a drum fixed to said spur wheel adjacent to 35 said chain lifter, bolts mounted to slide on said drum and adapted when slid in one direction to engage said chain lifter, ratchet pawls mounted on said drum adapted to

engage the said ratchet teeth on said chain lifter, a spur pinion gearing into said spur 40 wheel, a shaft on which said spur pinion is freely mounted, two sets of epicyclic gear on said pinion shaft one at each side of said pinion the ring of teeth engaged by the planet pinions of one of said sets of epicyclic 45 gear being on a brake drum fixed to one side of said pinion and the carrier for the planet pinions of the other of said sets of epicyclic gear being fixed to the other side of said pinion.

7. In a windlass, a shaft, a chain lifter freely mounted on said shaft, means for rotating said chain lifter, a brake drum, a free wheel device through which said chain lifter is connected to said brake drum 55 whereby notwithstanding the brake being on the chain lifter can be freely rotated in a hoisting direction, and ratchet and pawl mechanism whereby the chain lifter can be positively rotated in a lowering direction, 60 a spur wheel mounted to freely rotate on said shaft, means for connecting said wheel to said chain lifter a spur pinion gearing into said spur wheel, a shaft on which said spur pinion is freely mounted, two sets of 65 epicyclic gear on said pinion shaft one at each side of said pinion the ring of teeth engaged by the planet pinions of one of said sets of epicyclic gear being on a brake drum fixed to one side of said pinion and the carrier for the planet pinions of the other of said sets of epicyclic gear being fixed to the other side of said pinion.

Signed at London, England, this 17th day of August, 1918.

GEORGE THOMAS MACFARLANE.
